UNITED STATES PATENT OFFICE.

CARL KOPF, OF DURLACH, GERMANY.

MACHINE FOR MANUFACTURING FLEXIBLE METAL PIPES.

Application filed July 1, 1925, Serial No. 40,938, and in Germany July 8, 1924.

My invention relates to a machine by which flexible metal pipes can be manufactured from metal tubes provided with undulated walls, the undulations being jumped up whereby the previously rigid tube is converted into a flexible pipe.

The gist of the invention resides in the feature that the tools employed for jumping up the undulations serve also for the step-wise axial movement of the undulated tube or pipe whereby the machine is considerably simplified and its output is considerably increased.

My invention is illustrated diagrammatically and by way of example in the accompanying drawing in which Fig. 1 is a longitudinal section through one constructional form of the machine in the plane $a-a$ of Fig. 5, the metal pipe treated being shown in dotted lines in the left-hand part of the top of the machine; Fig. 2 is a cross-section in the plane $b-b$ of Fig. 4; Fig. 3 is a cross-section in the plane $c-c$ of Fig. 1; Fig. 4 is a side-view; Fig. 5 is a plan, partly in section in the plane $d-d$ of Fig. 2; and Figs. 6 and 7 show details which are also fully described hereinafter.

The machine consists in general of a body or frame to which the various operative members are attached. It is driven by means of the pulley 1 and the shaft 1^a which transmits the power to the cog-wheels 2 and 3 and the spur-wheels 4 5 6 and 7 (Figs. 1 and 2), whereby the shafts 8, 9, and 9^a are rotated.

There are two tool-slides 11 and two tool-slides 12 (Figs. 1, 6, and 7), each of them being so arranged as to be movable horizontally and having at its inner end a semi-circular recess (Fig. 2) adapted to engage the metal pipe. The slides 12 are arranged behind the slides 11. In Fig. 1 it is assumed that the slides 11 are closed so as to have grasped the tube, whereas the slides 12 are open, as in Fig. 2.

There are, furthermore, two cam-disks 22 and two cam-disks 24 which all are secured to the shaft 9^a which is rotated by a cog-wheel 7. The cam-disks 22 actuate the tool-slides 11 and the cam-disks 24 actuate the tool-slides 12. The power is transmitted from the cam-disks 22 to the tool-slides 11 by bell-crank levers 25, and from the cam-disks 24 to the tool-slides 12 by bell-crank levers 25. To close the tool-slides 12 the cam-disks 24 need be turned only for 20°,

whereby the work-piece will be grasped firmly between said slides whereupon the jumping up or, more precisely, another jumping up will take place and will be effected as described hereinafter.

The tool-slides 11 are located on a slide 17 which is common to them and can be moved in the direction to the tool-slides 12. The slide 17 is connected with two toggle-joint levers 13, to the joint of each of which is jointed a vertical rod 14 connected at its lower end with a one-armed lever 15 fulcrumed at 15^a to the body of the machine and provided at its other end with a roll 15^b co-operating with a cam-disk 16 affixed to the horizontal shaft 8 which is located below the slide 17 and parallel to it. It is obvious that the slide 17 with the tool-slides 11 can be moved towards, and away from, the tool-slides 12.

The position of the two slides 11 and 12 shown in Fig. 6 corresponds to the position of the same parts in Fig. 1, and also the configuration of the tube-parts (α , α^1 , α^2) shown in Fig. 6 corresponds to Fig. 1. The rigid tube to be converted into a flexible pipe is denoted α , whereas α^2 denotes a part of the finished flexible pipe produced by jumping up the undulations of the tube α . α^1 denotes the tube-part next to be jumped up, and this is effected by moving the slide 17 with the tool-slides 11 (which have grasped the tube α between them) towards the slides 12, the relative positions of the members concerned being then that shown in Fig. 7.

Between the two cam-disks 16 also two cam-disks 19 are secured to the shaft 8, and two one-armed levers 18 fulcrumed at 18^a to the body of the machine are connected with the levers 15 by draw-rods 20 whereby the levers 15 can be turned upwards and can lift the rods 14 so as to actuate the toggle-joint levers in such a manner that the slide 17 with the tool-slides 11 is withdrawn, these slides having, however, been opened prior thereto so that they can slide rearwardly over the next undulation of the undulated tube α .

The operations of the cam-disks 22 and 24 and of the cam-disks 16 and 19 are so timed relatively to one another that the sequence of the consecutive actions is as follows: Supposing, the slides 11 and 12 be in the position shown in Fig. 7, the slides 12 are being withdrawn, whereupon the pipe α will

be shoved automatically to the left by reason of the elasticity of the freshly made part of the pipe x^2 . Now the slides 12 are being moved towards one another so as to grasp the last undulations of the flexible pipe x^2 and secure them firmly in position; the slides 11 which had grasped and jumped up the undulation x^1 are withdrawn from the flexible pipe just for the axial length of an undulation of the tube x , and are then moved towards one another so as to grasp firmly said tube; now the slides 11 (always moved by the slide 17 and the members actuating it) are moved again to the left (from the position Fig. 6 into the position Fig. 7) so as to jump up the undulation lying next to the pipe x^2 . Now the slides 12 are again withdrawn from the flexible pipe x^2 , then again moved towards it so as to grasp it again, and so the cycle of operation proceeds continuously.

In the constructional form illustrated the slides 11 and 12 and the bell-crank levers 21 and 25 are connected with one another 26 not positively but by the intermediary of helical springs 23 and 26, whereby a certain yieldingness of the slides is provided and jamming is prevented.

Instead of attaching the cam-disks 22 directly to the shaft 9^a, I prefer to insert an eccentric sleeve 27, Fig. 4, by means of which said cam-disks can be so turned that the

slides 12 are kept in their outer position so as to facilitate the introduction of a fresh tube into the machine. This having been done, the sleeve is being turned back into its former position and the machine is then started when it will operate continuously in the manner described until the freshly introduced rigid undulated tube has been converted into a flexible pipe, as set forth. 40

I claim:

A machine for manufacturing flexible metal pipes from rigid undulated tubes, comprising, the combination with two pairs of tool-slides arranged one after another in the axial direction of the tube, of means for moving the slides of each pair towards, and away from, one another; another slide carrying one of said pairs, toggle-joint levers connected with this slide and adapted to move it towards, and away from, the other pair of the first-mentioned slides, draw-rods jointed to the joints of said toggle-joint levers, levers connected with the other ends 55 of said rods, crank-disks arranged to operate these levers, and means for rotating the several cam-disks, the said operating means being so timed that the said tool-slides are adapted to effect the axial step-by-step feed- 60 motion of the said tube, substantially as set forth.

In testimony whereof I affix my signature.
CARL KOPF.
